(57) **CLAIM**

The ornamental design for a watercraft as shown and described.

DESCRIPTION

FIG. 1 is a top, front, left-side perspective view of a watercraft, showing our new design;
FIG. 2 is a top, rear, right-side perspective view thereof;
FIG. 3 is a bottom, front, left-side perspective view thereof;
FIG. 4 is a bottom, rear, right-side perspective view thereof;
FIG. 5 is a front plan view thereof;
FIG. 6 is a rear plan view thereof;
FIG. 7 is a right-side view thereof;
FIG. 8 is a left-side view thereof;
FIG. 9 is a top plan view thereof; and,
FIG. 10 is a bottom plan view thereof.
The broken lines illustrate portions of the watercraft that form no part of the claimed design.
